UNITED STATES PATENT OFFICE.

JOSEPH BANCROFT WILSON, OF CHICAGO, ILLINOIS, ASSIGNOR TO WESTINGHOUSE ELECTRIC & MANUFACTURING COMPANY, A CORPORATION OF PENNSYLVANIA.

VALVE-OPERATING MECHANISM.

Application filed December 23, 1925. Serial No. 77,417.

My invention relates to valve operating mechanism, more particularly operating mechanism for the valves of prime movers, and has for an object to provide an apparatus of the character designated which shall be simple in design and easy of manufacture, capable of effecting close regulation of the valves operated, and which shall embody a minimum of linkage in the transmission of controlling movements.

A further object of my invention is to provide a fluid pressure operated relay device for a valve operating apparatus wherein the control valve is so designed that the power element thereof moves in increments responsive to displacement of the control valve without the intermediary of linkage between the valve and the power element.

Apparatus embodying features of my invention is illustrated in the accompanying drawings, forming a part of this application, in which Figure 1 is an end view of an elastic fluid turbine having my improved valve operating mechanism applied thereto; Figure 2 is a plan view of the relay employed with the apparatus; Figure 3 is a vertical sectional view of the relay taken along the line III-III of Figure 2 and drawn to a larger scale than Figure 2; and Figure 4 is a detailed view in perspective of the piston member and rotary valve embodied in the relay.

Heretofore, in the operation of prime movers of relatively large capacity, difficulties have been encountered in designing the valve operating apparatus therefor in such a manner as to avoid a multiplicity of external linkage. This has been especially true where the valves to be operated by the governing mechanism are of such size as to require the intermediary of a power operated relay between the governing mechanism and the valve, said relay operating in such a manner that the power element thereof moves in increments responsive to movements of the governing mechanism. The provision of a multiplicity of external linkage in a valve operating mechanism has been found objectionable because it complicates the apparatus and adds to its hazards of failure.

In accordance with my invention I provide governing apparatus embodying a well known form of centrifugal governor and

interpose, between the governor and the valve which it is to operate, a fluid pressure operated relay of such design that there is required a minimum of linkage between the governor and the relay. The relay operates by means of a rotary valve and a single acting piston, fluid pressure being employed to actuate the piston in one direction and biasing means for actuating it in the opposite direction. The relay valve is so designed that when it rotates the piston is moved in either direction by increments responsive to the angular displacement of the valve.

Referring now to the drawing for a better understanding of my invention I show in Fig. 1 a turbine 10 having a motive fluid supply conduit 11 and an admission valve 12. In the drawing, Fig. 1, the motive fluid supply conduit and the admission valve are shown relatively large for the purpose of clearness of illustration. At 15 is shown a well known form of centrifugal governor having an arm or lever 13 which rises and falls in response to increases and decreases in speed of the turbine in a manner well known in the art. The lever 13 transmits movements of the governor 15 to a relay 14, to be described later, through the intermediary of a single link 16.

At 17 is shown a pump, for example a gear pump, having a fluid discharge conduit 19. The pump 17 pumps fluid from a reservoir 21 and discharges it through the conduit 19 to the fluid pressure operated relay 14. At 22 is shown a by-pass conduit connecting the discharge conduit 19 and the intake conduit 18 and having disposed therein a relief valve 23. The by-pass conduit and the relief valve 23 serve to insure a predetermined pressure from the pump 17 to the relay 14. The relay 14 is supported from the admission valve 12 by means of a suitable framework 24. Movements of the power element of the relay 14 are transmitted to the admission valve 12 through a transverse member 26 which is connected to a pair of yoke members 27-27, which are in turn connected to the admission valve 12 through the intermediary of a second transverse member 28 and the valve stem 29. A spring 31 is employed for moving the admission valve and power element of the relay 14 in a direction for closing the valve

in a manner more particularly to be described later.

Referring now to Figures 3 and 4, the relay 14 embodies an operating cylinder 32 having disposed therein a single acting power element or operating piston 33. The operating piston 33 is provided with a relatively large stem portion 34 extending outwardly therefrom and which is connected to the transverse member 26 by means of a screw and nut connection 36. Fluid pressure is admitted to the under side of the piston 33 through a longitudinal passage 37, said passage extending longitudinally of the stem portion 34 through the piston 33. The longitudinal passage 37 is intersected by a diametral transverse passage 38 which extends entirely across the stem portion 34.

Surrounding the stem portion 34 of the piston 33 is a rotary valve 41 which is actuated by the governor arm 13 through the intermediary of the link 16 and a valve handle 42. The valve 41 is disposed within a housing 43 forming a part of the upper cover of the cylinder 32. A flange 44 is provided at the upper portion of the valve 41 in order to prevent longitudinal movements thereof while leaving it free to rotate with respect to the piston 33 and stem portion 34.

Provided in the valve 41 are a pair of diametrically opposed ports 46 and 47. The port 46 is connected at all times with the fluid pressure conduit 19 and the port 47 communicates with the upper end of the cylinder 32 by means of a passage 48, while the upper end of the cylinder 32 is open to the exhaust at all times through the intermediary of a conduit 49 which leads to the fluid reservoir 21.

The ports 46 and 47 are in the form of truncated triangles, or trapezoidal in form, and are so disposed that when the valve 41 is rotated one of the ports is opened and the other is simultaneously closed. For example, referring to Figure 4, if the valve 41 is rotated in a clock-wise direction the port 47 is rotated until the point A is opposite the transverse passage 38 closing one end of said passage, and the point B in port 46 is opposite the transverse passage 38. In this position fluid under pressure from the conduit 19 passes through the port 46 into the transverse passage 38 and from thence passes to the cylinder 32 beneath the piston 33 and forces the piston outwardly. The piston 33 moves outwardly until the passage 38 moves over the edge of the port 46 when no more fluid pressure can pass therethrough and the relay is in neutral or lap position. If the valve 41 be rotated in an anti-clock-wise direction from that shown in Figure 4 until the transverse passage 38 is opposite the point C, above the port 46, the port 47 rotates until the transverse passage is at the point D. In this position fluid beneath the

piston 33 is free to flow through the passage 37, transverse passage 38, passage 48 and conduit 49 to the exhaust. The spring 31 now forces the admission valve 12 in a closing direction and the piston 33 inwardly of the cylinder 32.

The movement just described continues until the stem portion 34 has moved downwardly a sufficient amount that the transverse passage 38 is again covered by the valve 41 and the relay 14 is again in neutral or lap position. It may thus be seen that for each movement of the governor 15 there is a definite movement of the power element of the relay 14 and that the admission valve 12 is opened or closed by definite increments responsive to movements of the governor 15 and to the angular displacement of the rotary valve 41.

When the turbine is at rest the governor arm 13 is at its lowest position and the port 46 is wide open. There being no pressure however in the conduit 19, the spring 31 forces the admission valve 12 closed and the piston 33 inwardly of the cylinder 32. In order that the turbine may be started I provide an auxiliary pump 51 which discharges through a conduit 52 to the conduit 19. The fluid under pressure thus admitted to the conduit 19 passes through the port 46, passages 38 and passage 37 to the under side of piston 33, opening the admission valve 12, and permitting the turbine to be started. A check valve 53 is provided in the conduit 52, to prevent back flow of fluid from the conduit 19 when the pump 17 is in operation and the turbine has been started.

From the foregoing description the operation of apparatus made in accordance with my invention will be apparent. When the turbine is running and there is an increment in speed the lever 13 of governor 15 is raised causing a rotation of the valve 41 in such a manner as to open the passage 38 of the stem portion 34 of the piston 33 to the port 47. Fluid beneath the piston 33 is now free to flow through the passage 38, passage 37 and port 47 to the exhaust and the spring 41 forces the admission valve 12 in a closing direction. This closing movement continues until the stem 34 has moved a sufficient amount that the passage 38 is blanked off from the port 47. Should there be a decrease in speed the lever arm 13 lowers and the valve 41 is rotated so that the passage 38 is placed in communication with the fluid pressure admission port 46 of the valve 41 and fluid under pressure passes through the port 46, the passage 38 and passage 37 into the operating cylinder 32 and forces the piston 33 outwardly of said cylinder opening the admission valve 12. This opening movement continues until the port 46 is blanked off by the valve 41, and is in direct proportion to the angular displacement of the valve 120.

41. So long as there is a steady load on the turbine 10 and no fluctuations in speed, the piston 33 is maintained in this position. If leakage occur through the piston 33 permitting it to move slightly inward, the passage 38 would again be in communication with the fluid pressure admission port 46 permitting a sufficient amount of fluid under pressure to pass through the passage 38 so as to maintain the piston 33 in its fixed position against leakage.

From the foregoing it will be apparent that I have devised an improved valve operating mechanism for a prime mover, embodying a fluid pressure operated relay, capable of effecting close regulation of the valve controlled and wherein a minimum of linkage is employed in transmitting movements of governing mechanism to the valve of the prime mover.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:—

1. The combination with a prime mover having a valve to be operated, of means responsive to the speed of the prime mover, and a fluid pressure operated relay for transmitting movements of the means responsive to speed to the valve, comprising an operating cylinder, a reciprocable piston therein, a stem for the piston having ports therein for the admission and exhaust of fluid under pressure thereto, a valve surrounding the stem and having fluid admission and exhaust ports cooperating with the ports of the piston stem, and operating means connecting the speed responsive means and the valve.

2. The combination with a prime mover having energy controlling means, of means responsive to the speed of the prime mover, and a fluid pressure operated relay for transmitting movements of the means responsive to speed to the energy controlling means, comprising an operating cylinder, a reciprocable piston therein, a stem for the piston having ports therein for the admission and exhaust of fluid under pressure thereto, a rotary valve surrounding the stem and having fluid admission and exhaust ports cooperating with the ports of the piston stem, and operating means connecting the speed responsive means and the valve for rotating the valve.

3. The combination with a prime mover having energy controlling means, of means responsive to the speed of the prime mover, and a fluid pressure operated relay for transmitting movements of the means responsive to speed to the energy controlling means, comprising an operating cylinder, a reciprocable piston therein, a stem for the piston having ports therein for the admission and exhaust of fluid under pressure thereto, a rotary valve surrounding the stem and having fluid admission and exhaust ports cooperating with the ports of the piston stem, and operating means connecting the speed responsive means and the valve for rotating the valve.

4. The combination with a prime mover having energy controlling means, of means responsive to the speed of the prime mover, and a fluid pressure operated relay for transmitting movements of the means responsive to speed to the energy controlling means, comprising an operating cylinder, a reciprocable piston therein, a stem for the piston having ports therein for the admission and exhaust of fluid under pressure thereto, a rotary valve surrounding the stem and having fluid admission and exhaust ports cooperating with the ports of the piston stem, and operating means connecting the speed responsive means and the valve for rotating the valve.

5. The combination with a prime mover having energy controlling means, of means responsive to the speed of the prime mover, and a fluid pressure operated relay for transmitting movements of the means responsive to speed to the energy controlling means, comprising an operating cylinder, a reciprocable piston therein, a stem for the piston having ports therein for the admission and exhaust of fluid under pressure thereto, a rotary valve surrounding the stem and having fluid admission and exhaust ports cooperating with the ports of the piston stem, said ports being adapted to simultaneously open and close upon angular displacement of the rotary valve, and operating means connecting the speed responsive means and the valve.

6. The combination with a prime mover having energy controlling means, of means responsive to the speed of the prime mover, and a fluid pressure operated relay for transmitting movements of the means responsive to speed to the energy controlling means, comprising an operating cylinder, a reciprocable piston therein, a stem for the piston having ports therein for the admission and exhaust of fluid under pressure thereto, a rotary valve surrounding the stem and having fluid admission and exhaust ports cooperating with the ports of the piston stem, said ports being adapted to simultaneously open and close an amount proportionate to the angular displacement of the rotary valve, whereby the operating piston is also moved an amount proportionate to the angular displacement of the rotary valve, and operating means connecting the speed responsive means and the valve for rotating the valve.

7. A fluid pressure operated relay for a valve operating mechanism comprising an operating cylinder having a reciprocable piston disposed therein with a stem extending outwardly of the cylinder, a longitudinally extending passage provided in the stem and passing through the piston, a transverse passage extending across the stem and intersecting the longitudinal passage, a rotatable valve surrounding the piston stem, opposed ports provided in the valve adapted to cooperate with the transverse passage of the piston stem for the admission and exhaust of motive fluid from the operating cylinder and adapted to open and close in response to angular displacement of the rotary valve, and means for rotating the valve.

8. A fluid pressure operated relay for a valve operating mechanism comprising an operating cylinder having a reciprocable piston disposed therein with a stem extending outwardly of the cylinder, a longitudinally extending passage provided in the stem and passing through the piston, a diametral passage extending across the stem and intersecting the longitudinal passage, a rotatable valve surrounding the piston stem, diametrically opposed ports provided in the valve adapted to cooperate with the transverse passage of the piston stem for the ad-

mission and exhaust of motive fluid from the operating cylinders and adapted to open and close in response to angular displacement of the rotary valve, and means for rotating the valve.

7. A fluid pressure operated relay for a valve operating mechanism comprising an operating cylinder having a reciprocable piston disposed therein with a stem extending outwardly of the cylinder, a longitudinally extending passage provided in the stem and passing through the piston for conveying pressure to and from one face of the piston, a transverse passage extending across the stem and intersecting the longitudinal passage, a rotatable valve surrounding the piston stem, a pair of elongated opposed ports provided in the valve and adapted to cooperate with the passage in the piston stem, each of said ports having a wall so extending as to narrow one of the ports at one end in the direction of rotation of the valve whereby the opposing ports are opened or closed upon rotation of the valve, means providing fluid pressure to one of the ports, an exhaust conduit connecting with the other port, means for rotating the valve, and biasing means for moving the piston in a di-

rection opposite to that when moved by the fluid pressure.

8. The combination with a prime mover having an admission valve, of a speed responsive mechanism for controlling the admission valve, and a fluid pressure operated relay for transmitting movements of the speed responsive mechanism to the admission valve comprising an operating cylinder, a piston disposed within the cylinder for moving the admission valve in one direction, a spring for moving the admission valve in the opposite direction, a stem portion provided on the piston extending outwardly of the cylinder and provided with ports and passages communicating with the active side of the piston, a rotatable valve surrounding the stem portion and having fluid pressure admission and exhaust ports adapted to cooperate with the ports in the stem portion upon rotation of the valve, and a single link connection between the speed responsive mechanism and the valve for rotating the valve.

In testimony whereof, I have hereunto subscribed my name this fourth day of December, 1925.

JOSEPH BANCROFT WILSON.
